UNITED STATES PATENT OFFICE

110,173

DESIGN FOR A LAMP SHADE OR SIMILAR ARTICLE

Paul S. Donchian, Hartford, Conn.

Application August 2, 1937, Serial No. 70,775

Term of patent 14 years

● *To all whom it may concern:*

Be it known that I, Paul S. Donchian, a citizen of the United States, residing at Hartford, in the county of Hartford and State of Connecticut, have invented a new, original, and ornamental Design for a Lamp Shade or Similar Article, of which the following is a specification, reference being had to the accompanying drawings, forming part thereof.

Fig. 1 is a perspective view of a lamp shade or similar article showing my new design;

Fig. 2 is a side elevation thereof;

Fig. 3 is a top plan thereof; and

Fig. 4 is a bottom plan thereof.

The present design is characterized as follows:

The lamp shade or similar article has a border-

rim formed of a series of elements, each of which may be defined as composed of a pentagonal pyramid and a triangular prism, one of the triangular faces of each of the pentagonal pyramids coinciding with one of the triangular faces of its complementary triangular prism, and a dome-portion extending away from the plane of the triangular faces of the triangular prisms remote from the said pentagonal pyramids. The pentagonal bases of the said pyramids form an outwardly-and-upwardly-sloping inner border-rim surface.

I claim:

The ornamental design for a lamp shade or similar article substantially as shown and described.

PAUL S. DONCHIAN.
